UNITED STATES PATENT OFFICE.

CHARLES W. SAALBURG, OF RICHMOND HILL, NEW YORK, ASSIGNOR TO MULTICOLOR INTAGLIO PRESS COMPANY, OF NEW YORK, N. Y., A CORPORATION OF DELAWARE.

METHOD OF TRANSFERRING CARBON-TISSUE PRINTS.

1,308,531.

Specification of Letters Patent.

Patented July 1, 1919.

Application filed February 27, 1917. Serial No. 151,165.

To all whom it may concern:

Be it known that I, CHARLES W. SAALBURG, a citizen of the United States, residing at Richmond Hill, in the county of Queens 5 and State of New York, have invented certain new and useful Improvements in Methods of Transferring Carbon-Tissue Prints, of which the following is a specification.

This invention relates to a method of 10 transferring photographically-sensitized carbon-tissue prints to copper or other etchable surfaces, and especially to those of rolls that are to be etched and used in multicolor printing. The object of the invention is to improve 15 the development of the gelatinous content of the face of said tissue prints, to transfer them without air blisters, wrinkles, or stretching or shrinkage in so far as is possible, so that they will in setting on the 20 surface to be etched be smooth thereon; and to moisten their paper backs when they have set, in such wise that when such backs are stripped off the stripping will not so disturb the gelatinous faces of the tissue 25 prints or the photographic images therein contained as to impair correct development.

In the accompanying drawings forming a part hereof and illustrating my invention in the best mode now known to me,

30 Figure 1 is a plan view of a layout mount of any suitable material on which are shown a plurality of photographically-sensitized carbon-tissue prints, each marginally secured by one of its safety margins to the 35 mount, and with its face of gelatinous content outward. This view shows the mount provided on its upper face with projecting gummed tabs the upper or face sides of which are gummable to the surface to be 40 etched.

Fig. 2 is an end view of a copper roll to be etched and of a squeegee roll, the layout mount having its print-carrying face opposed to the copper roll surface, and being 45 temporarily attached thereto by the projecting tabs; and the prints having their faces of gelatinous content opposed to the copper-roll surface. The view also indicates a spraying device.

50 Fig. 3 is a top plan view of a simple form of apparatus useful in practising this method.

Referring to the drawings, 1 is a copper-surfaced roll to be etched. It is indicated 55 as revolvable in an end bearing for its man-

drel 2. In practice a suitable apparatus will have two bearings 3, one for each mandrel end. A revolvable squeegee roll 4 is indicated as extending lengthwise along the upper periphery of the copper roll with its 60 axis rearward of the axis of the copper roll. In practice the apparatus will have two bearings, one for each end of the copper roll. The squeegee roll works as an idler. Its bearings are indicated by 5. A crank handle 65 6 is provided for the copper roll.

In practising my method I lay out on a preferably non-stretchable sheet mount 7 of bendable material such as good strong 70 smooth-surfaced paper of somewhat water-absorbent character, any desired number of photographically-sensitized carbon-tissue prints 8 securing each of such prints by its upper safety margin by dabs 9 of fish glue or other material easily soluble in water, 75 to the mount. The backs of the prints are opposed to the mount, the upper back margin of which I show provided with projecting tabs 10 corresponding ends of which are gummed to the back margin of the 80 mount and project away from the edge thereof. Each tab 10 is gummed on its front projecting face at 11.

The mount is rectangular or at least is cut with its upper or advancing edge 12 85 straight, and this straight edge of the mount is carefully aligned with a suitable guide-mark or guide-marks 13 which may be a series of aligned pencil marks on the copper roll. At least one of the side edges 14 of 90 the mount is made at right-angles to the advancing edge 12, and the copper roll is provided with a suitable guide-mark 15 which extends peripherally and is at right-angles to the guide-mark 13 which extends 95 lengthwise of the copper roll parallel with its axis. If desired, as a matter of convenience, the prints may be also stuck to the mount by patches of thin court plaster 16. A water trough 17 is provided for the copper roll and when the print or prints have 100 been transferred to the copper roll, and have set, I put hot water in the trough and rotate the copper roll, the prints and the mount in the hot water. This loosens up the mount 105 at its points of attachment to the copper roll and also loosens up the mount from the backs of the prints by dissolving the glue; and therefore I strip off the mount and then strip off the paper backs of the prints, leav- 110

ing on the copper roll merely the gelatinous films to be developed. For other rolls of the series corresponding prints are secured to the same mount or other mounts in exactly the same positions that the first series of prints has on its mount; and thereby I effect accurate registration of each coöperating print, one with another, in a series of etchable rolls for different colors.

- 10 The mount shown is provided with a series of location marks 15^a of any suitable kind to serve as guides in location on the same mount or on a series of mounts of duplicate prints; and all the mounts for a given series 15 are to have the guide-marks similarly placed on them.

If the apparatus indicated is used, I turn the copper roll, the squeegee roll being an idler, until the upper or advancing margin 20 of the mount is nipped by the squeegee roll and nipped and held in place not only by the weight of the squeegee roll, but also by the adhesive tab ends 11 sticking to the copper roll. By safety margins of carbon-tissue prints is meant that such margins do not contain any portion of the photographic image therein that it is desired to etch.

There are many other ways of positioning the gelatinous face or faces of the photographically sensitized carbon-tissue print or prints in opposition to an etchable surface, and it or they may be held in place by hand, but if manually manipulated the chances are that in getting a series of etchable rolls 35 ready for etching there will be so many errors that ultimate essential registration will be defeated. My process, while applicable to a single roll for monicolor printing, is nevertheless particularly directed to multicolor printing, and the prints on the mount 40 will be duplicated for the other rolls.

Having thus positioned the mount with its temporarily attached photographically-sensitized carbon-tissue prints in fixed alinement relatively to the axis of the roll, I lift the mount and the thereto attached carbon-tissue print or prints away from the copper roll as shown in Fig. 2, except at the nip between the copper and squeegee rolls; 45 and I carefully spray cool water into the bight or angular space between the opposing surfaces of the copper roll and lifted mount and prints for the purpose of softening the gelatinous content of the print faces 50 and making them adhesive. For the purpose of so gently and finely spraying the water, the spray pipe 18 is provided with a series of alined very small pinholes 19 close to one another. One end of the pipe is 55 plugged at 20 and the other end is connectible to a water-supply pipe, not shown, for bringing water under head into the spray pipe.

During such moistening step in which 60 flooding of the carbon tissue prints and

mount is avoided, and as the gelatinous faces of the prints become sticky, I squeegee the prints in place on the copper roll by turning it and subjecting the backs of the prints to the pressure of the squeegee roll 70 indirectly through the mount which I prefer generally to keep in place until the prints themselves have been smoothly squeegeed on the copper roll. I give the latter preferably only one turn.

If the paper backs of the carbon-tissue prints have become much wet in applying water into the bight mentioned, I carefully wipe them dry for I find that for the best results it is highly desirable to develop the 80 gelatinous face of the prints into an adhesive condition without any soaking of the paper back of the print, as such soaking of the paper back tends to cause it to stretch or wrinkle in drying and thereby to shrink 85 or stretch or wrinkle the photographically-sensitized face material of the print which has the gelatinous content and also contains the photographic image. The water-absorbing mount acts as a blotter and helps in keeping the paper print backs relatively dry. It is for this reason that an important 90 step of my method is to soften the print face with the least possible wetting of the paper back of the print, and thereby to complete 95 the transfer operation in a minimum of time in order to diminish the risk of shrinkage or stretch of the tissue.

I prefer to apply a very fine and delicate spray uniformly into said bight, using as 100 small an amount of moisture as requisite for development of the gelatinous content into adhesive condition. The carbon-tissue print is delicate to handle under the best of circumstances, and when it has an embedded 105 photographic image the required delicacy of treatment is enhanced. Such photographically-sensitized carbon-tissue prints, when moistened and squeegeed in place are liable to stretch and when they dry they are liable 110 to shrink, and they are also liable to wrinkles and blisters and devils, as is well known to all skilled in the art. Moreover such prints, or the material of which they are composed, are subject to peculiar variations 115 in part and in whole due to natural variations in temperature and hygrometric conditions.

What I claim is:

1. The process of transferring photographically sensitized carbon-tissue prints having face material of gelatinous content on a paper back, to the periphery of an etchable roll to be etched and subsequently used as a printing roll, consisting in attaching such a sensitized carbon-tissue print to a flexible mount with the back of the print opposed to the mount; in securing a margin of the mount to the etchable roll with the face of the print in position to contact with 120
2. The process of transferring photographically sensitized carbon-tissue prints having face material of gelatinous content on a paper back, to the periphery of an etchable roll to be etched and subsequently used as a printing roll, consisting in attaching such a sensitized carbon-tissue print to a flexible mount with the back of the print opposed to the mount; in securing a margin of the mount to the etchable roll with the face of the print in position to contact with 125
3. The process of transferring photographically sensitized carbon-tissue prints having face material of gelatinous content on a paper back, to the periphery of an etchable roll to be etched and subsequently used as a printing roll, consisting in attaching such a sensitized carbon-tissue print to a flexible mount with the back of the print opposed to the mount; in securing a margin of the mount to the etchable roll with the face of the print in position to contact with 130

the roll; in moistening the face of the print to develop adhesiveness in the face; in progressively squeegeeing the mount and print on the etchable roll by the rolling pressure 5 of a roll parallel to the etchable roll, and by such progressive pressure transferring the print to the etchable roll; in removing said pressure; in detaching the mount from the etchable roll and from the print back; and 10 in detaching the paper back of the print.

2. The process of preparing a series of multicolor etched printing rolls for use in a printing press, consisting in providing each 15 of a series of etchable printing press rolls with marks for obtaining registration of a series of etchings for successive colors; in transferring to each of said rolls and so positioning thereon by the aid of such marks, a carbon tissue print having a gelatinous 20 face and a paper back, with its gelatinous

face opposed to the roll and with the advancing marginal portion thereof in contact with the roll, and the remainder of the gelatinous face out of contact with the roll; in moistening the face of the print to make it 25 adhesive and to permit subsequent detachment of the paper back without excess saturation of the gelatinous material; in subjecting the adhesive print so located to a progressive pressure that molds it without 30 edgewise displacement on the roll; in stripping off the paper back; and in acidizing each of the series of prints to produce a series of etchings for different colors, one etching on one and another on another roll 35 of the series of printing rolls.

In testimony whereof I have hereunto set my hand this 16th day of February, 1917.

CHARLES W. SAALBURG.
